(57) **CLAIM**

We claim the ornamental design for a bracket for mounting a tablet shaped device, as shown and described.

DESCRIPTION

FIG. 1 is a perspective view of a bracket for mounting a tablet shaped device, showing our new design in a first configuration;

FIG. 2 is a back view thereof;

FIG. 3 is a front view thereof;

FIG. 4 is a right side view thereof;

FIG. 5 is a left side view thereof;

FIG. 6 is a plan view thereof;

FIG. 7 is a bottom view thereof;

FIG. 8 is a perspective view of the bracket for mounting a tablet shaped device of FIG. 1, shown in a second configuration;

FIG. 9 is a back view thereof;

FIG. 10 is a front view thereof;

FIG. 11 is a right side view thereof;

FIG. 12 is a left side view thereof;

FIG. 13 is a plan view thereof;

FIG. 14 is a bottom view thereof;

FIG. 15 is a perspective view of the bracket for mounting a tablet shaped device of FIG. 1, shown in a third configuration;

FIG. 16 is a back view thereof;

FIG. 17 is a front view thereof;

FIG. 18 is a right side view thereof;

FIG. 19 is a left side view thereof;

FIG. 20 is a plan view thereof; and,

FIG. 21 is a bottom view thereof.

(Continued)

The bracket for mounting a tablet shaped device is used to hold devices such as a smart phone. The broken lines illustrate environment and form no part of the claimed design.
